COLLAPSIBLE BAR.

Application filed July 28, 1924. Serial No. 728,544.

This invention relates to collapsible bars and the object of the invention is to improve the construction and operation of collapsible bars in the manner to be hereinafter described and claimed.

Referring to the drawings which accompany this specification and form a part hereof, which drawings illustrate an embodiment of this invention, and on which drawings the same reference characters are used to designate the same parts wherever they may appear in each of the several views, Fig. 1 is an elevation of a collapsible bar, parts being broken away; Fig. 2 is a plan view of the bar showing the parts in their collapsed position; Fig. 3 is an elevation of parts, drawn to an enlarged scale; Fig. 4 is a cross section taken on the line 4—4 on Fig. 3, looking in the direction indicated by the arrows; Fig. 5 is a plan view of the parts shown by Fig. 3; and Fig. 6 is an elevation of the parts shown by Fig. 3, but with parts shown as occupying different positions and with a part broken away.

Referring to the drawings, the reference numeral 1 designates, generally, a collapsible bar which is of such a character that it can be used for a side bar or a center bar for cots such as the kind shown, for example, in my pending application for Letter Patent for folding double cot, Serial Number 498,724, filed September 6, 1921. The collapsible bar 1 is illustrated as composed of cylindrical, wooden parts 2, 3 and 4 which are joined together by hinge members 5 and 6. Metal loops 7 are provided on one side of the bar to engage with hooks on a cot, not shown, and the hinge members 5 and 6 are so constructed and arranged as to prevent bending or deflection in one direction while the bar is in use. The drawings illustrate the cylindrical, wooden rods or parts 2, 3 and 4 as provided with flat seats 8 to receive flat, metal hinge members 9 which have no special characteristics of construction except that each is provided with a shoulder 10 and is adapted to be immovably secured to its part of the bar. Link hinge members 11 are provided with shoulders 12 and 13 adapted to abut the shoulders 10 on the coacting hinge members 9 to prevent further relative movements of the parts in one direction while permitting freedom of movement with re-

spect to each other in the opposite direction. The drawings illustrate a simple manner of providing the link hinge members 11 with shoulders 12 and 13. The link hinge members 11 are illustrated as made from sheet metal with a lip 14 and the edge 15 of the lip 14 is bent over into the plane of the shoulders 10 on the coacting hinge members 9.

The hinge pins 16, which are illustrated by the drawings as rivets, pass through two hinge members 9, two link hinge members 11 and a part of the bar. In order to secure the hinge members 9 to the parts of the bar immovably, that is to say, so that they cannot rotate with respect to hinge pins 16, either the metal loops 7 or rivets 17 may be used as securing means.

The method of extending or collapsing the bar will be obvious from the foregoing description and from an inspection of the drawings, but it should be noted, referring to Fig. 1 of the drawings, that the part 2 can be folded down under the part 3 and that the part 4 can be folded up over the part 3, and the question might arise how can the bar ever be rigid with such a construction. It should be noted that the bar is supported by the metal loops 7 when in use, and by reason thereof relative folding of the sections of the bar is prevented. When the bar is removed from the hooks, it may be readily collapsed, as shown for instance in Fig. 2.

It will be obvious to those skilled in the art that the present improvements are susceptible to various changes and modifications and it is not desired, therefore, to limit or restrict the same to the particular construction or arrangement of parts herein illustrated and described, except where limitations appear in the appended claims.

The invention claimed is:

1. A hinge of the character described comprising a plurality of hinge plates adapted to be secured to the adjacent ends of the parts to be hinged together, said plates having their confronting end portions notched to provide opposed abutments, a pivot pin associated with each of said plates, and a hinge link plate mounted on said pins and extending between said hinge plate, said hinge link plate having a reduced lip along one edge thereof, said reduced lip having an inturned

edge flange, the ends of which provide rigid shoulders engageable with the rigid abutments afforded by said notches.

2. A hinge of the type described comprising a plurality of hinge plates adapted to be secured to the adjacent ends of the parts to be hinged together, said hinge plates being formed with opposed rigid abutments, a pivot pin associated with each of said hinge plates and a hinge member mounted on said pins and extending between said hinge plates, said hinge member being formed with rigid

and unyielding shoulders designed to engage with said rigid abutments to limit relative movement of said parts in one direction, said shoulders and the portions of the hinge member between the same being subjected to compression and shearing stresses only and being entirely relieved of bending, twisting or distorting strains.

In witness whereof I hereto affix my signature.

NEWTON N. BROWN.
